UNITED STATES PATENT OFFICE.

OSCAR ANDERSON, OF JERSEY CITY, NEW JERSEY.

ROPE CLAMP.

Application filed May 18, 1926. Serial No. 110,034.

This invention relates to rope clamps more particularly adapted for securing wire ropes or cables such as used with hoisting machines, etc.

5 An object of the invention is to provide a rope clamp which is comparatively simple and is adapted to hold a rope or cable securely and reliably at all times when the parts are properly adjusted; that is to say, 10 the rope clamp is preferably so constructed that from time to time, as the holding action of the clamping parts may become weaker, the adjusting of the clamping parts may be made so as to more strongly hold the rope or 15 cable, the clamp being preferably specially constructed with that end in view.

These being among the objects of the present invention, the same consists of certain features of construction and combinations of parts to be hereinafter described and then claimed with reference to the accompanying drawings illustrating the preferred embodiment of the invention, in which:

20 25 Figure 1 is a plan of the improved clamp; Figure 2 is a side elevation;

Figure 3 is a longitudinal section on the line 3—3 Figure 1;

Figure 4 is a plan of the shank and head 30 of the clamp stripped of all movable parts; and

Figures 5 and 6, respectively, are transverse sections on the lines 5—5 and 6—6 Figure 1.

35 Referring to the drawings, the main body of the clamp comprises a shank 10 provided at one end with a suitable connecting member which member may be in the form of a head 11 which is preferably forked, 40 and through the fork there passes a bolt 12 over which, or over a sheave thereon there may pass a rope which is to do the pulling or raising. The rope or cable 13 is adapted to be operated by a hoisting machine or the 45 like, and the main object of the clamp is to secure the rope 13 firmly thereto.

The shank 10 is provided with a raised portion 14 which is located intermediately of the normally dimensioned portions of the 50 shank, so as to project outwardly from one face of the shank. A depression 15 longitudinally of the shank is formed in the raised portion 14, such depression being of generally V-shape in cross-section, so that 55 the opposite walls of the depression diverge outwardly. The side walls of the longitudi-

nal depression 15 are provided with two series of teeth 16, 17, each series extending longitudinally of the depression, and the biting edges of the teeth extending outwardly away from the bottom of the depression, so that they are transverse of the inner faces of the raised portion 14. Preferably each tooth is formed transversely, similar to a ratchet tooth, with inclined surfaces and square shoulders, the square shoulders and hence the biting edges of the teeth being presented inwardly away from the outer extremity of the shank 10. These teeth may or may not extend the full depth 70 of the depression 15, and preferably they extend from a point slightly above the bottom of the depression and taper inwardly from their outer ends towards the bottom of the depression. 75

80 A pair of holes 18 is formed through the extremity of the shank 10, and another pair of holes 19 is formed in the shank at a point between the raised portion 14 and the head 11, that is to say, said holes 18, 19 are formed through the thinner portions of the shank. Another pair of holes 20 is formed in the shank at a point about midway of the two pair of holes 18, 19, the holes 20 passing through the raised portion 14 of the shank, 85 and those portions of the holes which pass through said raised portion being open to the depression 15. It will be seen that the holes 20 are in a plane intersecting the two series of teeth 16, 17, so that there is one hole at the same side of the depression as the series of teeth 16 and another hole 20 at the same side as the series of teeth 17.

90 Clamping bolts 21, 22, 23 are passed through the holes in the shank, and preferably these bolts are of U-shape, the free ends thereof having threads 24 onto which may be turned nuts 25. U-bolt 21 is passed through the pair of holes 18, and U-bolt 22 is passed through the pair of holes 19, these two bolts 21, 22 being located beyond the ends of the raised portion 14. U-bolt 23, which is passed through the holes 20, is located about midway between the two bolts 21, 22. The bottom of the longitudinal depression is formed with rounded humps 26, 27, the hump 26 being located between the bolts 21, 23, and the hump 27 between the bolts 22, 23. 100

105 In using the clamp to anchor a rope or cable 13 thereto, the end of the cable is passed between the opposite side portions of

each bolt so as to be located under the saddle portions of the two bolts, and between them and the shank 10. When the nuts 25 are tightened up the saddle portions of the U-bolts will cause the rope or cable 14 to be forced into the longitudinal depression 15. It will be seen that when the U-bolts are drawn in as far as possible, the portions of the rope or cable between the bolts will be caused to be forcibly pressed against the biting edges of the two series of teeth, 16, 17, and as the teeth are located in the spaces between the bolts, the bolts will have a tendency to pull the intermediate portions of the rope or cable more closely towards the shank 10, thereby more or less kinking the rope so that the rope is firmly held by the bulldog-like gripping action of the teeth and cannot slip. The ratchet tooth-like formation of the teeth and the positioning of the biting edges thereof towards the head 11 of the shank tend to hold the rope the more securely the greater the pull on the rope. It is clear that as the end of the rope to be gripped wears more or less, or may have a tendency to become loose, the bolts may be freely tightened up firmly upon the rope so as to force the rope further into the longitudinal toothed depression 15, and as the depression is of V-shape the rope will still be held firmly and securely by the tightened up bolts. If the rope or cable be of smaller diameter to start with than is illustrated in the drawings, or if a rope of the size shown becomes so worn and grooved that it has to be still further tightened up, it will be seen that the rope will eventually be brought to bear upon the humps 26, 27. These humps 26, 27 formed in the bottom of the depression 15 will produce a more or less decided kinking of the rope or cable 13, because those portions of the rope which are engaged by the bolts will be forced as far as possible towards the shank 10, while the intermediate kinked portions of the rope will be slightly elevated over the engaging surfaces of said humps, and thereby these humps together with the clamping action of the bolts will firmly and securely hold the rope.

It is obvious that the invention is susceptible to more or less modification and that parts may be added, omitted, or substituted without departing from the spirit and scope of the invention as expressed in the appended claims.

What I claim as new is:

1. In a rope clamp, the combination of a clamping shank having a head and provided with a longitudinal depression for receiving a rope, a series of teeth at each side of the

depression and each tooth extending vertically thereof, the teeth being of ratchet-tooth shape and their short sides presented toward one end of the head end of the depression, threaded U-shaped, rope clamping bolts passing through the shank for spanning the rope, at the sides of the depression, and nuts screwed onto the bolts, at the back of the shank.

2. In a rope clamp, the combination of a clamping shank having a head, and provided with a longitudinal depression for receiving a rope, a series of teeth at each side of the depression, three U-shaped, threaded, rope-clamping bolts passing through the shank for spanning the rope, at the sides of the depression, the intermediate bolt intersecting the two series of teeth, and the end bolts being located beyond the ends of the depression, and nuts screwed onto the bolts, at the back of the shank.

3. In a rope clamp, the combination of a clamping shank having a connecting member and provided with a longitudinal depression for receiving a rope, a series of teeth at each side of the depression, three U-shaped, threaded, rope-clamping bolts passing through the shank for spanning the rope, at the sides of the depression, the intermediate bolt intersecting the two series of teeth, and the end bolts being located beyond the ends of the depression, and nuts screwed onto the bolts, at the back of the shank, the bottom of the depression provided with rope-bending humps located in the spaces between said bolts.

4. In a rope-clamp, the combination of a clamping shank having a connecting member at one end and provided with a longitudinal depression for receiving a rope, a series of teeth at each side of the depression and each tooth extending vertically thereof, the teeth being of ratchet-tooth shape and their short sides presented toward that end of the depression beyond which said connecting member is located, threaded rope clamping bolts passing through the shank at the sides of the depression, and nuts screwed onto the bolts.

5. In a rope-clamp, the combination of a clamping shank having a connecting member at one end and provided with a longitudinal depression for receiving a rope, a series of teeth at each side of the depression, three threaded rope clamping bolts passing through the shank at the sides of the depression, the intermediate bolt intersecting the two series of teeth and the end bolts being located beyond the ends of the depression, and nuts screwed onto the bolts.

OSCAR ANDERSON.
